His Attorney.

UNITED STATES PATENT OFFICE.

KARL ALQUIST, OF NEW YORK, N. Y.

GEARING FOR MARINE PROPULSION AND THE LIKE.

Application filed March 19, 1920. Serial No. 367,158.

To all whom it may concern:

Be it known that I, KARL ALQUIST, a subject of the King of Sweden, residing at New York, county of New York, State of New York, have invented certain new and useful Improvements in Gearing for Marine Propulsion and the like, of which the following is a specification.

The present invention relates to marine propulsion and more particularly to the transmission of power from a prime mover to the propeller shaft of a vessel through spur gearing.

It is now known that in a rough sea the power thus transmitted is subject to wide variations, the period of the variations being substantially dependent upon the pitching of the vessel. The prime mover, generally a steam turbine revolving at a high speed, has a comparatively large fly wheel capacity, while the propeller with its shaft and the driven portion of the gear have a small wheel capacity. In the case of a double reduction gearing, the prime mover and high speed end of the gearing may be considered a high speed system, and the propeller and low speed end of the gearing a low speed system. The body of water in which the propeller rotates will, due to the action of the waves, periodically vary its speed relatively to the ship in the direction of motion of the ship and it thus may happen that at times the propeller, instead of being driven by the gear, is driven by the water. When this happens, the prime mover referred to will speed up the system, but in a heavy sea it may happen that the propeller is accelerated by the water at a higher rate than that of the prime mover, due to the unequal fly wheel effects of the two ends of the system before referred to. In such a case, the normal driving portion of the gear will be driven, resulting in a shifting of the teeth in mesh through the clearance space to contact on the other sides of the teeth. The continuity of the driving pressure and contact is thus broken and when the normal direction of drive is reestablished, i. e., when the propeller "hits the water again" there results a large, temporarily increased pressure on the gear teeth due to the speeding up of the system during the period described, and this pressure is further increased by a blow between the teeth. Also when the pinion does not drive, it generally moves endwise from its normal position and, when

the drive comes on, will oscillate with blows before steadyng down. It is evident that the increase in pressure between the gear teeth due to the blows is substantial, and as the life of the gear is dependent upon keeping down their maximum pressure peaks as far as possible, the importance of maintaining the continuity of drive and avoiding such blows is apparent.

The object of my invention is to provide an improved structure and arrangement in a gearing for marine propulsion whereby the above referred to difficulties will be overcome, and for a consideration of what I believe to be novel and my invention, attention is directed to the following description and the claims appended thereto.

In the drawing, Fig. 1 is a diagrammatic plan view of a gearing embodying my invention, and Fig. 2 is an end view thereof.

Referring to the drawing, 5 indicates a propeller shaft driving a ship's propeller 6. On the shaft 5 is a low speed gear wheel 7 which is shown as meshing with two low speed pinions 8 and 9 mounted on intermediate speed shafts 10 and 11 respectively. On shafts 10 and 11 are high speed gear wheels 12 and 13 with which mesh high speed pinions 14 and 15 carried by driving shafts 16 and 17 respectively. Driving shafts 16 and 17 may be connected to suitable prime movers such as elastic-fluid turbines, an arrangement as shown being well adapted for use in connection with a high pressure turbine and a low pressure turbine connected in series as regards the flow of operating fluid. The foregoing forms a double reduction gearing, pinions 14 and 15 and gear wheels 12 and 13 forming the high speed end, and pinions 8 and 9 and gear wheel 7 forming the low speed end. High speed gear wheels 12 and 13 are shown as being of the flexible type invented by me and comprising a plurality of disks or plates rigidly fastened together at their central portions and spaced slightly apart at their peripheries to permit of axial yielding under excessive tooth pressure.

Now, according to my invention, I make the low speed gear wheel 7 of rather large diameter thereby increasing its fly wheel effect and provide it and the low speed pinions 8 and 9 with which it meshes with single helical gear teeth of small angle, for example about 5 degrees. I then provide for each of the intermediate speed shafts 10

and 11 suitable thrust bearings 18 and 19 which firmly hold the intermediate speed parts of the gearing against axial movement. The high speed end of the gearing 5 has preferably double helical teeth as shown. With this arrangement when a reversal of end thrust occurs on the propeller shaft and gear wheel 7 becomes a driving gear there will be a comparatively gentle shifting over 10 of the tooth pressures to the other side of the teeth by movement through the small clearance between the teeth. And when the load comes on the propeller again, it will be taken up by a shifting back of the low speed gear 15 wheel 7. Since the teeth of the low speed end of the gearing are single helical and the intermediate speed shaft or shafts is or are held from axial movement by the thrust bearings, there can occur under no circumstances 20 any violent axial shiftings or vibrations of the low speed end of the gearing such as may occur for example with double helical gearing in the low speed end. The reason for this is that with double helical 25 teeth on the low speed end of the gearing the intermediate speed portion of the gearing, i. e., the intermediate speed shaft or shafts which carry the low speed pinions and the high speed gear wheels is liable to 30 slide axially toward one end under the force of gravity or for other reasons when the load is taken off the propeller by the propeller being driven by the water, and when the load suddenly comes on again, the intermediate speed portion of the gear being 35 then driving on one helix, is violently moved back axially and overruns its middle position and drives on the other helix after which it will be thrown back again, thus 40 oscillating with hard blows a few times for each period the load is thrown on. These blows are especially destructive. With my improved arrangement, I hold the intermediate speed portion of the gearing firmly 45 against movement in an axial direction by the thrust bearings 18 and 19 with the result that an action such as that just described cannot take place.

Since gear wheel 7 has a large diameter, 50 its width will be comparatively small and hence the length and diameter of the low speed pinion or pinions meshing therewith will have satisfactory proportions.

Furthermore on account of the small angle of the teeth on gear wheel 7, it is able 55 to move axially thereby following the "breathings" or small movements of the main thrust bearing for the propeller shaft

without any appreciable effort on the rest of the gearing. At the same time the smooth 60 running characteristics of helical gearing is retained even though the helical angle is comparatively small. The main thrust bearing for the propeller shaft does not show in the drawing, but it will be understood 65 that it is of the usual type for taking the axial thrust of the propeller shaft.

In accordance with the provisions of the patent statutes, I have described the principle of operation of my invention, together 70 with the apparatus which I now consider to represent the best embodiment thereof; but I desire to have it understood that the apparatus shown is only illustrative, and that the invention may be carried out by 75 other means.

What I claim as new and desire to secure by Letters Patent of the United States, is,—

1. In a ship propulsion gearing, the combination of a propeller shaft, a low speed gear wheel mounted thereon, said gear wheel having single helical teeth of an angle of the order of five degrees, a high speed pinion, an intermediate speed shaft carrying a low speed pinion, and a high speed gear wheel which mesh with said low speed gear wheel and high speed pinion respectively, said high speed pinion and high speed gear wheel being of the double helical type and said low speed pinion being of the single helical type for meshing with the low speed gear wheel, and a thrust bearing for said intermediate speed shaft to take the axial thrust of the single helical low speed pinion. 80

2. In a ship propulsion gearing, the combination of a propeller shaft, a low speed gear wheel mounted thereon, said gear wheel having single helical teeth of an angle of the order of about five degrees and being of 85 comparatively large diameter whereby its fly wheel effect will be large, a high speed pinion, an intermediate speed shaft carrying a low speed pinion and a high speed gear wheel which mesh with said low speed gear wheel and high speed pinion respectively, said high speed pinion and high speed gear wheel being of the double helical type, and said low speed pinion being of the single 90 helical type for meshing with the low speed gear wheel, and a thrust bearing for said intermediate speed shaft to take the axial thrust of the single helical low speed pinion. 95

2. In a ship propulsion gearing, the combination of a propeller shaft, a low speed gear wheel mounted thereon, said gear wheel having single helical teeth of an angle of the order of about five degrees and being of 100 comparatively large diameter whereby its fly wheel effect will be large, a high speed pinion, an intermediate speed shaft carrying a low speed pinion and a high speed gear wheel which mesh with said low speed gear wheel and high speed pinion respectively, said high speed pinion and high speed gear wheel being of the double helical type, and said low speed pinion being of the single 105 helical type for meshing with the low speed gear wheel, and a thrust bearing for said intermediate speed shaft to take the axial thrust to the single helical low speed pinion. 110

In witness whereof, I have hereunto set my hand this tenth day of March, 1920.

KARL ALQUIST.
